(57) **CLAIM**

The ornamental design for a pin extraction tool as shown and described.

DESCRIPTION

FIG. 1 is a top plan view of an ornamental design for a pin extraction tool of the present invention;

FIG. 2 is a rear plan view of an ornamental design for a pin extraction tool of the present invention;

FIG. 3 is a front plan view of an ornamental design for a pin extraction tool of the present invention;

FIG. 4 is a left side view of an ornamental design for a pin extraction tool of the present invention;

FIG. 5 is a right view of an ornamental design for a pin extraction tool of the present invention;

FIG. 6 is a bottom plan view of an ornamental design for a pin extraction tool of the present invention;

FIG. 7 is an upper isometric view of an ornamental design for a pin extraction tool of the present invention; and,

FIG. 8 is a lower isometric view of an ornamental design for a pin extraction tool of the present invention.
